Application July 22, 1932, Serial No. 623,941

8 Claims. (Cl. 221—69)

This invention relates to supports and more particularly to a rack for supporting a plurality of grease or other lubricant guns adapted to be used in performing different lubricant servicing operations.

One of the objects of the present invention is to provide a novel grease gun rack in which a plurality of grease guns are supported by a single upright member.

10 Another object of the present invention is to provide a novel grease gun rack in which a plurality of grease guns are supported in substantially the same horizontal plane.

Still another object is to provide a novel grease gun rack in which a plurality of grease guns are supported by a single member which also provides a convenient receiver for waste material.

15 A further object is to provide a novel grease gun rack having a removable receptacle for waste material so that the receptacle may be removed and emptied as and when convenient.

20 A further object is to provide a novel grease gun rack having a rotatable mounting whereby any desired gun may be readily presented to an operator. The rack may also be mounted for portability so that it may be moved about for convenient disposition to any place desired.

25 A still further object is to provide a novel grease gun rack having a horizontal plate for carrying oil cans, tools or similar articles.

30 A still further object is to provide a novel specialized lubrication service rack in which a plurality of dispensing pumps having indicia are associated with a chart bearing corresponding indicia and legends to inform an operator which pump to use for each of a series of servicing operations.

35 Other objects and advantages will appear from the following detailed description when taken in connection with the accompanying drawings showing embodiments of the present invention. It is to be expressly understood that the drawings are for the purpose of illustration only and are not to be taken as a definition of the limits of the invention, reference being had for this purpose to the appended claims.

40 In the drawings in which similar reference numerals indicate similar parts throughout the several views:

45 Fig. 1 is a view partly in section and partly in elevation showing one embodiment of the present invention;

50 Fig. 2 is a similar view of another embodiment of the invention;

Fig. 3 is a plan view of the embodiment shown in Fig. 2, and

Fig. 4 shows a chart constituting a part of the present invention.

Referring particularly to Fig. 1 there is shown therein one embodiment of the present invention constituted by a base 10 supporting an upright member 11 which carries spaced horizontal plates 12 and 13 to which a plurality of rack members or clips 15—16, respectively, are suitably secured 5 as by rivets. Grease guns or dispensing pumps 17 for lubricants are detachably secured in adjacent pairs of rack members 15 and 16 and each gun bears a suitable indicium, for example a numeral such as indicated at 18 for a purpose which 10 will appear more fully hereinafter. The upright member 11 is hollow and is provided at its upper end with a funnel shaped member 19 to facilitate the depositing therein of dirty oil or grease or other waste material, a suitable receptacle 20 15 being supported below the lower end thereof in any desired manner, as by clips 21 carried by the base, for receiving the waste material from the member 11, the receptacle 20 being readily removable so that it may be emptied by the operator 20 at convenient intervals. The funnel-shaped member 19 is also adapted to carry the nozzles of 25 guns of the type having a length of flexible hose between the gun and the nozzle so that any grease dripping from the nozzles will be conducted 30 through the member 11 into the receptacle 20. The horizontal plates 12 and 13 provide a convenient means for carrying oil cans, rags, waste and similar articles useful or convenient in servicing a machine. In order that the rack may be 35 readily moved from place to place the base 10 is preferably provided with rollers or casters 22, although if desired these may be omitted and the base placed in one position in which it is adapted 40 to remain.

Referring particularly to Figs. 2 and 3 there is shown therein another embodiment of the invention substantially similar to the embodiment shown in Fig. 1 with the further feature that the upright member 11 is rotatably mounted in the base 10. In this embodiment the base 10 is provided with a suitable sleeve member 23 secured thereto in any suitable manner and adapted to receive the lower end of the upright member 11 so that the latter member will be 45 freely rotatable therein. The lower plate 12 rests on the upper end of sleeve 23 and is freely rotatable thereon, a suitable bearing surface being provided between these two members. In using the rack shown in Figs. 2 and 3, if an op-

erator desires to use one of the guns upon the opposite side of the rack, he has merely to rotate the member 11, to which plates 12 and 13 are secured, in the sleeve 23 until the desired gun is on the side adjacent to him without the necessity of rotating the entire rack on its casters or of walking around it.

In order to inform an operator which one of a series of guns or pumps to use for a particular servicing operation, a chart such as that shown in Fig. 4 is provided bearing indicia corresponding to the indicia on the pumps respectively and legends related to the indicia indicating the particular servicing operation to be performed by the pump having an indicium corresponding to the indicium related to the legend. As shown such indicia are constituted by the numerals 24 corresponding respectively to the numerals 18 on the pumps and legends 25 opposite the numerals 24 identifying the servicing operation to be performed. If desired the legends 25 may also inform an operator what particular type or consistency of grease or other servicing fluid each particular pump is adapted to contain. As shown the legends 25 relate to the guns or pumps carrying lubricant for the operations to be performed in servicing an automobile but it is to be expressly understood that the same are adapted equally well to identify the operations to be performed in lubricating or otherwise servicing any other desired piece of machinery.

In using a rack constructed according to the present invention an operator determines from the chart shown in Fig. 4 the indicium which corresponds to the gun or pump for the particular operation he desires to perform and then selects from the rack the pump bearing that indicium. In this manner the operator is assured at all times of having a pump containing the correct servicing fluid and peculiarly adapted to perform the particular servicing operation. If it is desired to move from place to place the rack may be readily moved on its rollers and may be easily and quickly revolved about its vertical axis to facilitate selection of the particular gun desired.

Thus there is provided by the present invention a novel grease gun rack in which a plurality of grease guns or dispensing pumps are supported in substantially the same horizontal plane, in which a novel waste material receptacle is provided, in which the rack is rotatable and portable, and in which means are provided for supporting oil cans, waste and the like. There is also provided a novel specialized servicing rack in which an operator is informed as to which of a plurality of dispensing pumps containing different servicing fluids to utilize for a particular servicing operation.

While only two embodiments of the present invention have been shown and described, it is to be understood that the same is not limited thereto but may be embodied in various forms. Thus various forms of rack members or supports might be employed or other changes might be made as will be apparent to one skilled in the art without departing from the scope of the invention. Reference will therefore be had to the appended claims for a definition of the limits of the invention.

What is claimed is:

1. A grease gun rack comprising a base, a tubular upright member supported by said base adapted to receive waste material through its upper and lower end, horizontal supporting mem-

bers secured to said upright member, a plurality of racks carried by said horizontal members cooperating with the upper end of said tubular upright member for supporting a plurality of grease guns in a position in which the drip from the nozzles is trapped by the tubular member, and a receptacle carried by said base below said tubular upright member for receiving any waste material which may be deposited in said upright member.

2. A grease gun rack comprising a base, a tubular upright member supported by said base and adapted to receive waste material, a funnel-shaped member on the upper end of said upright member for conducting waste material thereinto, a receptacle detachably supported upon said base at the lower end of said upright member for receiving waste material therefrom, and a plurality of racks carried by said upright member and cooperating therewith for supporting a plurality of grease guns respectively in a position in which the drip from the nozzles is received by the funnel shaped member.

3. A grease gun rack comprising a base, a tubular upright member supported by said base and adapted to receive waste material, a flaring member on the upper end of said upright member to conduct waste material thereinto, a receptacle mounted upon said base adjacent the lower end of said upright member to receive waste material therefrom, plates having the form of shallow receptacles carried by said upright member, and a plurality of racks carried by said plates for supporting a plurality of grease guns respectively in a position in which the drip from the nozzles thereof will be received by the tubular member.

4. A grease gun rack comprising a tubular upright support adapted to receive waste material through its upper and open end, a receptacle supported upon said base at the lower end of said support to receive waste material therefrom, a plurality of spaced plates carried by said support, and a plurality of rack members carried by said plates adapted to support a plurality of grease guns respectively in a position in which the drip from the nozzles thereof will be received by the tubular member.

5. A grease gun rack comprising a tubular upright support adapted to receive waste material through its upper and open end, a receptacle supported upon said base at the lower end of said support for receiving waste material therefrom, a plurality of spaced discs carried by said support and a plurality of rack members secured to the periphery of each of said discs and adapted to support a plurality of grease guns respectively in a position in which the drip from the nozzles thereof will be received by the tubular member.

6. A grease gun rack comprising a base, a tubular upright member rotatably supported by said base and adapted to receive waste material through its upper and open end, a receptacle supported upon said base at the lower end of said tubular member to receive waste material therefrom, and a plurality of racks disposed about the periphery of said upright member adapted to support a plurality of grease guns respectively in a position in which the drip from the nozzles thereof will be received by the tubular member.

7. A grease gun rack comprising a base, a tubular upright member rotatably supported by said base and adapted to receive waste material through its upper and open end, a receptacle supported upon said base at the lower end of said tubular member and adapted to receive waste

- material therefrom; a pair of spaced discs secured to said upright member, and a plurality of racks secured to the periphery of said discs adapted to support a plurality of grease guns respectively in
- 5 a position in which the drip from the nozzles thereof will be received by the tubular member, said discs and upright member adapted to be rotated in said base to present any desired one of said grease guns on the side adjacent an operator.
- 10 8. A grease gun rack, for holding grease guns having grease dispensing nozzles attached thereto, comprising, an upright tubular member, a base for supporting said member, racks secured to said upright member for supporting said grease guns in upright positions with the discharge ends of the guns uppermost, a receptacle mounted upon the upper end of the tubular member and communicating therewith for receiving the dispensing nozzles of said grease guns when located upon said racks and a waste grease receptacle removably mounted upon said base in a position beneath the lower and open end of said tubular member for receiving grease which may extrude from the 10 nozzles after the guns have been placed upon the racks.
